UNITED STATES PATENT OFFICE.

WILLIAM H. GRINDLEY, OF CONGLETON, ENGLAND.

DESIGN FOR A COVERED DISH.

SPECIFICATION forming part of Design No. 29,570, dated November 1, 1898.

Application filed September 9, 1898. Serial No. 690,604. Term of patent 8½ years.

To all whom it may concern:

Be it known that I, WILLIAM H. GRINDLEY, a subject of the Queen of Great Britain, residing at Congleton, Chester, England, have 5 invented and produced a new and original Design for a Covered Dish; and I do hereby declare the following to be a full, clear, and exact description of the same, reference being had to the accompanying drawings, forming 10 part thereof.

Figure 1 is a top view of the covered dish embodying my design. Fig. 2 is a side view, and Fig. 3 an end view, of the same.

The following are the leading features of 15 my design:

The body of the dish *a* is divided into two parts—an upper part *b*, contracted inwardly until it terminates in the upper rim of the dish, and a lower part *c*, contracted inwardly 20 and sharply toward the bottom, where it terminates in the foot *d*. The line of demarcation between these two parts is designated *e* in the drawings. It is curved downward to its greatest extent at *e'* in the middle of each 25 side of the dish. It is then curved upward on each side, and then downward, and then upward again to form a short scallop *e''*, of which there are four, symmetrically placed around the dish, two on each side. It is again 30 curved upward and then downward to pass around the ends of the dish at *e'''*. The lower part of the body of the dish *c* is thus composed, in effect, of eight curved panels—viz.,

two end panels *m* and *n*, two side panels *q*, one on each side, and four intermediate panels, two, *o* and *o''*, on each side, these panels having the scallops *e''* for the upper boundaries. In a similar manner the upper part *b* of the body of the dish is divided into eight panels—viz., two side panels *x* and *x'*, two 40 end panels *y* and *y'*, to the middle portions of which the handles *h* are secured, and four small intermediate panels *z* and *z'*, two on each side.

The cover of the dish *d* is similar in outline 45 to the upper rim of the body of the dish, into which it fits and overlaps. In the middle is placed a top handle. On each side of the cover are three panels *i j k*, each of which is highest in the middle and which slope 50 downward convexly from the handle, reverse, and turn concavely downward, and then again reverse and turn sharply downward and outward to the rim or edge of the cover. Similarly two panels *r* and *s* finish out the ends 55 of the cover.

What I claim is—

The design for a covered dish substantially as shown and described.

In witness whereof I have hereunto set my 60 hand, this 26th day of August, 1898, in the presence of two subscribing witnesses.

WILLIAM H. GRINDLEY.
